UNITED STATES PATENT OFFICE.

CLARENCE H. BARTON, OF INDIANAPOLIS, INDIANA, ASSIGNOR TO INTERNATIONAL HARVESTER COMPANY, OF NEW JERSEY, A CORPORATION OF NEW JERSEY.

BALL-ROLLING MACHINE.

1,264,139.

Specification of Letters Patent. Patented Apr. 30, 1918.

Application filed August 10, 1914. Serial No. 856,089.

To all whom it may concern:

Be it known that I, CLARENCE H. BARTON, a citizen of the United States, residing at Indianapolis, in the county of Marion and 5 State of Indiana, have invented certain new and useful Improvements in Ball-Rolling Machines, of which the following is a full, clear, and exact specification.

This invention relates to ball rolling machines.

Twine placed on the market is made up into balls of definite sizes and shapes. After the balls have been removed from the balling machines such balls do not always present a smooth surface; that is, some of the turns may be a little higher or lower than the adjacent turns. These balls, for commercial use, should be uniform in size and shape, and should present a smooth hard 15 surface devoid of any irregularities which would cause the twine to loosen accidentally.

The main object, therefore, of this invention is to give balls of twine a hard, smooth and uniform surface.

Another object of this invention is to provide a simple, compact and inexpensive machine for automatically feeding said balls thereinto, rolling said balls, and automatically discharging said balls.

These and other objects are accomplished by providing a ball rolling machine having means for feeding the balls into the machine, means for rolling the balls, and means for automatically discharging said balls 35 from said machine; balls thus treated being adapted to meet all requirements of commercial usage.

The invention is illustrated on the accompanying sheets of drawings, in which—

40 Figure 1 is a side elevation of my ball rolling machine;

Fig. 2 is an end view thereof;

Fig. 3 is a sectional view of the same machine taken in the plane of line 3—3 of 45 Fig. 2; and

Fig. 4 is a detail view of part of the controlling mechanism.

The various novel features of my invention will be apparent from the description 50 and drawings, and will be particularly set forth in the appended claims.

This balling machine includes a main frame 10 having a guiding run-way 11 in which the balls roll when discharged from 55 the operating rollers to be referred to later.

Secured to this main frame is a supplemental frame 12 in which two shafts 13 and 14 are mounted. Mounted upon one end of shaft 13 is a beveled gear 15, (see Fig. 2), meshing with a beveled gear 16 mounted 60 upon a power shaft 17. On the opposite end of the shaft 13 is secured another beveled gear 18 meshing with a beveled gear 19 secured to a shaft 20 supported in brackets 21 and 22. Also secured to the shaft 20 65 is a beveled gear 23 meshing with a beveled gear 24 on one end of the shaft 14. Secured to the shaft 13 is a roller 25, and secured to the shaft 14 is a roller 26. Intermediate the beveled gears 19 and 23 and 70 mounted on the shaft are two parts 27 and 28 of a clutch, the part 27 being rotatably secured to the shaft and slidably mounted thereon, and part 28 being loose on said shaft. The clutch part 27 has a groove 29 75 for the reception of a fork 30 secured to a rod 31 slidably mounted in the brackets 21 and 22, there being a spring 32 interposed between bracket 21 and fork 30 tending to keep the clutch parts 27 and 28 out 80 of engagement with each other. Formed integrally with clutch part 28 and being loose on the shaft 20 is a worm 33 meshing with a worm gear 34 mounted on one end of a small shaft 34 to the other end of 85 which is secured a spur gear 35 which meshes with a spur gear 36 loosely mounted on shaft 18.

Pivots secured at 37 to the frame 12 is a bell crank lever 38, to one arm 39 of which 90 is secured one end of a spring 40, the other end of which is secured to bracket 21, which spring tends to hold the projection 41 of arm 42 of the bell crank lever in engagement with a portion of the fork 30 to lock 95 the clutch parts 27 and 28 in engagement with each other in opposition to the action of spring 32. The arm 39 of the bell crank lever lies in the path of a projection 44 formed integrally with the worm gear 34. 100 This projection engages the arm 39 of the bell crank lever for swinging the lock or projection 41 out of engagement with the fork 30 to permit the spring 32 to separate clutch part 27 from clutch part 28. The 105 clutch part 27 periodically is thrown into engagement with the clutch part 28 by a cam 45 formed on one side of a ratchet wheel 46, which ratchet wheel is actuated by an eccentric 47 mounted on the shaft 20, 110

and working in an elongated opening 48 of a swinging arm 49 pivoted on a stud 50 secured to bracket 22. This arm 49 is provided with a pawl 51 which transmits motion in one direction to the ratchet wheel from the eccentric 47, said arm also having another pawl 52 for preventing said ratchet from rotating in the opposite direction.

Secured to one side of the spur gear 35 is a crank shaft 54 to which is connected a link 55 having an elongated opening 56 for slidably receiving a rod 57 mounted in arms 58 pivotally connected to a support 59. When the link 55 is actuated in an upward direction the rod 57 is engaged by the bottom of the opening 56, forcing the arms 58 upwardly, and also the roller 60 journaled in the ends of said arms. At the same time arm 61, which is pivotally mounted on the shaft 14 and connected to one of the arms 58 by link 62, is also raised for feeding a ball from the supply inclined run-way 63 into the machine and between the rollers 25, 26 and 60.

The balls are discharged from between the rollers 25, 26 and 60 by an arm 64 loosely mounted upon the shaft 13 and actuated by a projection 65, formed integrally on one side of the spur gear 36, said projection 65 engaging a projection 66 on said arm 64, the arm 64 rotating in a counter-clockwise direction for lifting the balls from between the rollers 25 and 26, the roller 60 at that time being in a raised position. A projection 67 is also formed integrally with the spur gear 36 for limiting the falling movement of the arm 64 after it has passed through an angle of 180° from the position shown in Fig. 3. The operation of the machine as a whole will now be considered.

Let it be assumed that the parts are in the position shown in Fig. 1 of the drawings, there being a ball 69 between the rollers 25, 45 26 and 60, the rollers 25 and 26 being rotated continuously through the transmission connections from power shaft 17, and roller 60 being rotated intermittently through the rotation of the ball 69, which 50 is rotated by the rollers 25 and 26. During this rotation of the rollers, which receive their motion through shaft 20, the ratchet wheel 46 is also being slowly rotated through said shaft 20 and eccentric 47. The rolling 55 of each ball 69 between the rollers is of comparative long duration, corresponding to about 340° of movement of the ratchet wheel 46. During the remaining 20° of movement of the ratchet wheel 46, the clutch 60 parts 27 and 28 are thrown into engagement with each other for causing the ejection of the ball between the rollers and the feeding in of another ball, the clutch parts then being thrown out of engagement with each 65 other. This closing of the clutch causes the

actuation of worm gear 34 and the projection 44 thereon. Due to the fact that the cam 45 is elongated, the projection 44, while rotating in a clockwise direction, as indicated by the arrow, passes out of engagement with the arm 39 of the bell crank lever 38 before the cam 45 passes away from rod 31, thereby permitting the spring 40 to swing the bell crank lever into a position to lock the clutch parts 27 and 28 into engagement with each other in opposition to the action of the spring 32. After this takes place the cam 45 passes out of engagement with the rod 31. As the spur gear 35 now continues to rotate with worm gear 34 the spur gear 36 is also caused to rotate, the projection 65 eventually passing into engagement with the projection 66 on the arm 64 for raising the said arm to eject the ball 69 from between the rollers 25, 26 and 60, the roller 60 having been raised sufficiently for this purpose in the meantime by the link 55 and pin 57 engaging the bottom portion of the elongated opening 56 in said link. As the ball 69 is ejected from between the rollers 25 and 26 the member 61 passes into engagement with the next ball 75 on the supply run-way 63 to move said next ball into position between the rollers 25 and 26. As the machine continues to operate the roller 60 and member 61 are gradually lowered, due to their own weight.

When the worm gear 34 has completed a revolution the projection 44 again passes into engagement with the arm 39 of the bell crank lever 38 for forcing the lock portion 41 out of engagement with the yoke 30 to permit the spring 32 to separate the clutch parts 27 and 28, whereupon the worm 33, worm gear 34, spur gears 35 and 36 are arrested from further movement. The ball just placed between the rollers of the machine continues to be rolled until the cam 45 and ratchet wheel 46 makes a complete revolution, and cam 45 passes into engagement with the rod 31 to again throw clutch part 27 into engagement with clutch part 28, whereupon the above described operation is repeated. It is seen, therefore, that the balls are automatically fed into the machine and between the rollers, automatically rolled to give them a hard, smooth and uniform surface, and automatically discharged from between the rollers, rendering the operation simple and inexpensive.

It is evident that there may be various modifications of my invention, and it is my intention to cover all such modifications which do not depart from the spirit and scope of my invention as set forth in the appended claims.

What I claim is:

1. In a ball rolling machine, the combination of means for rolling balls, means for feeding wound balls to said rolling

- means, and means separate from said rolling means for discharging said balls therefrom.
2. In a ball rolling machine, the combination of means for rolling formed balls, 5 means for automatically feeding balls to said rolling means, and positive means distinct from said rolling means for discharging said balls therefrom.
3. In a ball rolling machine, the combination of means for rolling formed balls, 10 means for feeding balls to said rolling means, and positive means separate from said rolling means for automatically discharging said balls.
- 15 4. In a ball rolling machine, the combination of means for rolling formed balls, means for automatically feeding balls to said rolling means, and a member separate from said rolling means for automatically 20 discharging said balls.
- 25 5. In combination, means for automatically feeding wound balls into a rolling device, and a member movable relative to said rolling device for automatically discharging 25 said balls therefrom.
- 30 6. In a ball rolling machine, the combination of means for rolling formed balls, means for feeding balls to said rolling means, positive means for discharging balls therefrom, and means independent of said rolling 35 means for controlling the operation of said feeding and discharging means.
- 35 7. In a ball rolling machine, the combination of means for rolling formed balls, means for feeding balls to said rolling means, positive means for discharging balls therefrom, and unitary means for controlling the operation of said feeding and discharging means.
- 40 8. In a ball rolling machine, the combination of means for rolling balls, means for feeding balls to said rolling means, a member for discharging said balls, means for controlling the operation of said feeding 45 means and discharging member, and means for locking said controlling means.
- 45 9. In a ball rolling machine, the combination of means for rolling balls, means for feeding balls to said rolling means, means for actuating the said feeding means, means for locking said actuating means in operative position, and means for disengaging said lock.
- 50 10. In a ball rolling machine, the combination of means for rolling balls, means for feeding balls to said rolling means, means for discharging balls therefrom, means for actuating said feeding and discharging means, means for locking said actuating 55 means in an operative position, and means for releasing said locking means.
- 55 11. In a ball rolling machine, the combination of a plurality of rollers, a member for feeding balls between said rollers, a 60 member for discharging balls from between said rollers, and a clutch member for controlling said feeding and discharging members.
- 65 12. In a ball rolling machine, the combination of a plurality of rollers, a member for feeding balls between said rollers, a member for discharging balls from between said rollers, a clutch member for controlling said feeding and discharging members, a lock for holding said clutch in an operative 70 position.
- 70 13. In a ball rolling machine, the combination of a plurality of rollers, a member for feeding balls between said rollers, a member for discharging balls from between said rollers, a clutch member for controlling said feeding and discharging members, a lock for holding said clutch in an operative 75 position, and means for actuating said lock to permit the opening of said clutch.
- 75 14. In a ball rolling machine, the combination of a plurality of rollers, a member for feeding balls between said rollers, a member for discharging balls from said rollers, a clutch for controlling the actuation 80 of said feeding and discharging members, a cam for throwing said clutch into operative position, a lock for said clutch, and means for releasing said lock.
- 80 15. In a ball rolling machine, the combination of a plurality of rollers, means for raising one of said rollers and feeding a wound ball into said machine, and means for controlling said above mentioned means.
- 85 16. In a ball rolling machine, the combination of a plurality of rollers, and means for automatically raising one of said rollers for discharging a formed ball from between said rollers and for feeding another ball between said rollers.
- 90 17. In a ball rolling machine, the combination of a plurality of rollers, means for automatically raising one of said rollers for discharging a ball from between said rollers and for feeding another wound ball between 95 said rollers, and means for controlling said above mentioned means.
- 95 18. In a ball rolling machine, the combination of a plurality of rollers, means for shifting one of said rollers for feeding a ball between said rollers and for discharging a ball from between said rollers, a clutch for controlling the actuation of said means, a cam for actuating said clutch into an operative position, a lock for said clutch, and means for releasing said lock.
- 100 19. In a ball rolling machine, the combination of a plurality of rollers, means for actuating said rollers, means for feeding a ball to said rollers, means for discharging said ball from said rollers, and automatically operated means for actuating said feeding means and said discharging means.
- 105 20. In a ball rolling machine, the combination of a plurality of rollers, means for 110

continuously actuating certain of said rollers, means for intermittently changing the position of another of said rollers, automatically operated feeding and discharging means associated with said rollers, a shoot coöoperating with said feeding means, and a run-way into which the balls are discharged.

21. In a ball rolling machine, the combination of a plurality of rollers, means for continuously actuating certain of said rollers, intermittently operated means for actuating another of said rollers, and means for actuating said last mentioned means.

22. In a ball rolling machine, the combination of a plurality of rollers, automatically operated means for intermittently changing the position of one of said rollers, continuously operated means for actuating certain other of said rollers, and means actuated by said continuously operated means for controlling said intermittently actuating means.

23. In a ball rolling machine, the combination of means for rolling wound balls, and a member movable relative to said rolling means for discharging balls from said rolling means.

24. In a ball rolling machine, the combination of means for rolling wound balls,

and a member movable transversely with respect to said rolling means for automatically discharging balls from said rolling means.

25. In a ball rolling machine, the combination of means for rolling balls, means for discharging balls from said rolling means, and means for controlling said discharging means.

26. In a ball rolling machine, the combination of means for rolling balls, means for feeding balls to said rolling means, driving mechanism for said feeding means, including a lock, and a lock controlling member for said driving mechanism.

27. In a ball rolling machine, the combination of means for rolling balls, means for discharging balls from said rolling means, driving mechanism for said discharging means, including a lock, and lock controlling means for said driving mechanism.

In testimony whereof I affix my signature, in the presence of two witnesses.

CLARENCE H. BARTON.
